UNITED STATES PATENT OFFICE

1,992,380

RETAINING DEVICE FOR INTERCHANGEABLE MAGAZINES OF FIREARMS

Friedrich Linder, Dusseldorf, Germany, assignor to Rheinische Metallwaren- und Maschinenfabrik, Dusseldorf, Germany, a corporation of Germany

Application November 20, 1933, Serial No. 698,896
In Germany March 8, 1933

4 Claims. (Cl. 42—50)

In arms for continuous fire of the type in which the ammunition is fed from detachable magazines, the catch which holds the magazine firmly in the magazine housing of the weapon, consists generally of a lever pivoted in the magazine housing, which under the influence of a spring engages behind a projection in the magazine which has been thrust or swung into the magazine housing in a condition ready for feeding. 5 In consequence of the shaking of the gun during continuous fire, and particularly when it is fired with depression, the magazine lever is apt to be forced out of its locked position against the influence of the spring releasing the magazine; 10 the operation of the firearm is then involuntarily interrupted. If the magazine retaining spring is strengthened in order to overcome this drawback, this gives rise to other drawbacks. The feeder spring in the magazine whose function it 15 is to cause the platform to release the magazine retaining catch after the last cartridge has been thrust out, would likewise have to be strengthened and this would involve difficulties in charging and also in increased frictional resistance to 20 movement of the breech.

According to the present invention, the movable magazine retaining member, which may be a sliding member or a lever, is bolted in its locked position by a safety member co-operating with 25 magazine projections, in such a manner that the magazine retaining member normally locked by it, on the insertion of a magazine and also when a magazine becomes empty is automatically released at the proper time for movement into the locking 30 position.

The drawing shows a typical embodiment of the invention in horizontal section through the magazine housing of an automatic firearm.

In the magazine housing *a* of the gun there is 40 located in known manner the magazine *b* which is adapted to be thrust in, and from which the cartridges *c*, *c*₁ are thrust forward into the path of the breech *e* by the pressure of the feeder spring *d*₁ which acts on the platform *d*. The 45 magazine is provided on the right-hand side, as seen in the drawing, with a projection *b*₁, against a shoulder *b*₂ of which a magazine retaining latch *f*, pivotally mounted in the magazine housing about a pin *f*₁, engages under the pressure of a spring *g*₂, which acts on it through a safety lever *g* pivoted on a pin *g*₁.

The safety lever *g* has a shoulder *g*₃ the profile of which is curved concentrically to the pivotal axis *g*₁, and bears against a correspondingly curved shoulder *f*₂ on the retaining latch *f*, there-

by bringing it into the locked position and at the same time locking it against swinging back. The locking is brought about by the relatively eccentric position of the pivotal axes *f*₁, *g*₁ of the latch *f* and lever *g* in conjunction with such an arrangement of the bearing surfaces *f*₂, *g*₃ that the action exercised by the retaining latch *f* on the safety lever *g* in its effort to disengage from the locking position as a result of shocks, are directed towards the pivotal axis *g*₁ of the 10 said lever or run so that they tend to swing the safety lever in the anti-clockwise, locking sense of rotation which locks it. Thus, normally the retaining latch *f* is in its locking position and is held therein, no matter whether a magazine *b* 15 is introduced into the weapon or not.

The safety lever *g* has a finger *g*₄ extending in front of the retaining latch *f* into the path of the magazine projections *b*₁ and platform projection *d*₂, which projections co-operate with the retaining latch, to move the safety lever into a position releasing the latch *f*. The retaining latch *f* is thus released both on the insertion of the magazine when a temporary displacement occurs by the action of the magazine projection *b*₁, and also when, after the last cartridge has been thrust from the magazine, the projection *d*₂ of the platform encounters the finger *g*₄ and tends to swing it out of its locked position for unbolting the magazine. Further, to permit removal of a 30 completely full or partially full magazine, on the magazine housing there is provided a handle (not shown in the drawing) which, when reversed, first transfers the safety lever *g* into the position releasing the retaining lever *f*, and then carries the 35 retaining lever with it.

I claim:—

1. In a firearm comprising a magazine, a magazine housing on the arm, and mechanism for retaining the magazine in the housing, the combination of a projection on the magazine having a retaining shoulder, a latch in the housing movable into and out of retaining engagement with said shoulder, a safety member normally locking the latch in its shoulder retaining position, 40 a follower in said magazine having a projection, and a finger on the safety member extending into the paths of both said projections and co-operating therewith to unlock the latch.

2. In a firearm comprising a magazine, a magazine housing on the arm, and mechanism for retaining the magazine in the housing, the combination of a projection on the magazine having a retaining shoulder, a latch in the housing movable into and out of retaining engagement with 45

said shoulder, a pivoted safety member having a surface concentric with its pivot and bearing on the said latch for locking the latter in shoulder-retaining position, a follower in said magazine having a projection, and a finger on the safety member extending into the paths of both said projections and co-operating therewith to unlock the latch.

3. In a firearm comprising a magazine, a magazine housing on the arm, and mechanism for retaining the magazine in the housing, the combination of a projection on the magazine having a retaining shoulder, a latch pivoted in the housing for movement into and out of retaining engagement with said shoulder, a safety member pivoted about an axis spaced from the axis of the latch and having a surface concentric with its pivot and bearing on said latch with increasing pressure when the latch moves to release

position owing to the spacing of said axes, and a finger on the safety member extending into the paths of both said projections and co-operating therewith to unlock the latch.

4. In a firearm comprising a magazine, a magazine housing on the arm, and mechanism for retaining the magazine in the housing, the combination of a projection on the magazine having a retaining-shoulder, a latch in the housing movable into and out of retaining engagement with said shoulder, a safety member normally locking the latch in its shoulder retaining position, a follower in said magazine having a projection, and a finger on the safety member extending in front of the latch in the direction of magazine insertion and protruding into the path of both said projections and co-operating therewith to unlock the latch.

FRIEDRICH LINDER.
